TIRE REPAIR GUN

Samuel E. Nakis, 8701 Delmar, St. Louis County, Mo.

Filed May 14, 1965, Ser. No. 85,286

Term of patent 14 years

(Cl. D54—13)

FIG. 2

FIG. 1

FIG. 3

FIG. 4

FIG. 5

FIGURE 1 is a side elevational view of the tire repair gun, the opposite side being a mirror image thereof;
FIGURE 2 is a top plan view thereof;
FIGURE 3 is a bottom plan view thereof;
FIGURE 4 is a rear elevational view thereof; and
FIGURE 5 is a front elevational view thereof.
I claim:

The ornamental design for a tire repair gun, as shown and described.
